United States Patent Office

Des. 210,335

Patented Feb. 27, 1968

210,335

DISPLAY RACK

Clark B. Rollins, Jr., 1415 Elm Hill Road,
Nashville, Tenn. 37210

Filed May 19, 1967, Ser. No. 7,209

Term of patent 14 years

(Cl. D80—10)

Fig. 1

Fig. 2

FIG. 3

FIG. 1 is a front perspective view of a display rack embodying my new design;

FIG. 2 is a side elevational view thereof; and

FIG. 3 is a top plan view thereof.

I claim:

The ornamental design for a display rack, as shown.
